UNITED STATES PATENT OFFICE.

JAMES CARAFILIDIS, OF SABRATON, WEST VIRGINIA, ASSIGNOR OF THREE-TENTHS TO JAMES DELAS, OF GREENSBURG, PENNSYLVANIA, AND ONE-FIFTH TO VASEL SAVIDIS, OF MORGANTOWN, WEST VIRGINIA.

TIN OPENER.

Application filed April 29, 1922. Serial No. 557,258.

This invention relates broadly to sheet separating devices, and more specifically to mechanism for opening sheet metal packs.

The primary object is to provide a machine of the type commonly termed "sheet openers" or "tin openers", embodying means whereby the bonds by which the sheets are caused to adhere are positively broken.

A further object is to provide a machine of the character mentioned by which the various sheets of the pack are individually stripped or severed from the adjacent sheets.

A still further object is to provide a machine into which the entire pack is fed and by which the various sheets of the pack are wholly separated without human intervention.

With these and other objects in view, the invention resides in the features of construction, arrangement of parts and combinations of elements which will hereinafter be fully described, reference being had to the accompanying drawings, in which—

Figure 1 is a top plan view of the invention;

Figure 2 is an enlarged transverse section taken substantially on line 2—2, Fig. 1;

Figure 3 is a side elevation of the feed-roll housing and driving gears;

Figure 4 is a top plan view of the same;

Figure 5 is a side elevation of the blade-carrying and actuating mechanisms;

Figure 6 is a top plan view of the same;

Figure 7 is an enlarged sectional elevation of the pack-advancing and supporting mechanism, showing the knockers and tongs;

Figure 8 is an elevation of the channeled face of the gear segment or wheel;

Figure 9 is a section of the same on line 9—9, Fig. 8;

Figure 10 is a detail view in front elevation of the tongs and knocker;

Figure 11 is an inner face view of the finger-carrying mechanism; and—

Figure 12 is an outer side elevation of finger adjusting means.

Referring to said drawings, 1 indicates housings in which is journaled a plurality of pairs of feed rolls, as 2, 3 and 4, of which an intermediate pair, as 3, is preferably corrugated for producing slight bond-breaking corrugations in the pack, while the final pair 4 is plain for restraightening the pack. The pack is entered between said pairs of

rolls over a feed table 5 and is advanced by said rolls to a position in which it rests upon a platform 6 with its front end extending somewhat over or beyond the front end of said platform. At a predetermined moment in the operation of the machine, suitable lifting magnets 7 are carried rearward to a point over the front end of the pack and are then advanced, drawing said pack forward therewith, as will hereinafter be fully explained.

In the position to which it has been advanced by said magnets 7, each of the opposite front corners of the pack is struck by one of the heads 8 of a knocker 9 which is carried by a rearwardly rotating shaft 70 or spindle 10 which is journaled in the adjacent side of a frame 11, the sides of said frame being disposed in approximate alignment with the housings 1. The engagement of the knocker-heads 8 with the corners of the pack results in the corners of the lowermost sheet of the pack being forcibly bent downward away from the next-above sheet and a slight separation of the front end of said sheet from the overlying one. Following this, a pair of knife-like blades 12 carried horizontally by heavy chains 13 located at opposite sides of the machine outside of and parallel to the sides of the frame 11 enter the intermediate space provided by the foresaid separation of the front end of the lowermost sheet from the overlying sheet of the pack. Said blades, which occupy substantially aligned and substantially meeting relation, are drawn rearward horizontally throughout the length of the pack thus effecting complete separation of the lowermost sheet and allowing the latter to drop to an underlying bed 14, from which it may be removed by hand or other appropriate means.

Power for driving the various sets of rolls 2, 3 and 4 is communicated through suitable gearing, as that shown in Figs. 1 and 3, from a suitably located drive shaft, 100 as 15, which may be directly driven by an electric motor 16. A pulley or sprocket wheel 17 carried by one of the sets of feed rolls, as the one of the rolls of the pair 4, is connected by belt or chain 18 to a pulley or sprocket wheel 19 carried by the end of a roller 82 located rearward of the table 6. A pulley 83 carried by the opposite end of

- said roller is connected by a chain or belt 84 to a pulley or sprocket 85 carried by a shaft 20 which is journaled at a suitable elevation in upright members 11^a of the frame 5 11. Mounted upon said shaft 20 intermediate said frame members so as to rotate with said shaft is a wheel 21 having a suitable portion of its periphery provided with gear teeth 21^a adapted to operatively engage the 10 teeth of a longitudinally disposed rack-bar 22 by which the lifting magnets 7, hereinbefore referred to, are supported. Said rack-bar is mounted and longitudinally slidable upon a bar or rod 23 which has its opposite 15 ends mounted upon supports 24 and 25 which are carried transversely of the frame 11 adjacent to the front and rear ends of the latter and above the path of travel of the pack.
- 20 A long spiral spring 86 is carried by the rod 23 intermediate the transverse support 25 and the rear end of the rack-bar. Said spring is designed to forcibly thrust said rack-bar to its advanced position for carrying forward the pack supported by the magnets 7 following the retraction of said rack-bar which is induced by engagement therewith of the gear segment constituted by the teeth of the wheel 21. A short and relatively light spring 27 is interposed between the front end of said rack bar and the support 24, said spring serving merely as a buffer for relieving the shock of the practically instantaneous return movement of the rack-bar following its release by the gear segment.
- 25 A spring 28 is carried by the shaft 20 between the wheel 21 and one of the frame members 11^a, whereby said wheel is normally held in an inoperative position with respect to the rack-bar 22. The opposite face of said wheel has formed therein a spiral channel 29 within which, in the rotation of said wheel, rides the point of a finger 30 which is pivotally mounted upon an arm 44 carried by a vertical bar 31. Said bar is supported by an inwardly directed arm 32 carried by the upper end of a toothed bar 33, having its upper end projected 30 through said arm and having a head 34 that rests upon a light coil spring 35 which has its lower end seated upon said arm. Said bar 31 has its lower end vertically movable in a vertical guideway 36 provided therefor 35 in a box-like guide member 37 which is loosely suspended on said shaft 20.
- 35 The toothed bar 33 is vertically adjustable, having the teeth thereof engaged with a toothed wheel 38 rotatable upon a spindle 39 carried on the inner face of the adjacent frame member 11^a, while the back of said bar rests against a portion of said frame member, as against an inwardly directed web 40 formed on said member. Said bar has the various teeth thereof numbered to facilitate adjustment thereof to suit packs composed of varying numbers of sheets. As shown in Fig. 12, the designating numbers are carried by the outer face of the bar and are visible through a vertical slot 41 provided in the adjacent frame member. When a sheet metal pack is introduced in the machine, the bar 33 is adjusted to a position in which a suitable pointer 42 carried by the spindle 39 indicates on said bar a numbering corresponding to the number of sheets forming the pack. A pin 43 is then directed through the frame member 11^a into a position engaging a tooth of the toothed wheel 38 whereby the latter is locked against rotation, thus locking the bar 33 against movement from its adjusted position. In such position of the bar 33, the finger 30 occupies a position in the channel 29 of the wheel 21 at such a distance from the center channel 35 outlet that, in the operations required to effect separation of the various sheets of the pack, it will have traversed said channel to the inner end of the latter. At the conclusion of the pack opening operation, the said finger rides from said inner end of the channel to the central elevated surface of said wheel and, in doing so, acts to thrust said wheel 21 forward against the tension of spring 28 to a position in which it overlies the rack-bar 22, in which position it operatively engages said rack-bar for shifting the latter rearward to a position for taking up the next pack. Having thrust the wheel 21 into operative relation to the rack-bar, as 40 aforesaid, the spring 35, which has gradually been compressed through the downward pull exerted upon the bar 31 in the downward travel of the finger, acts to instantly elevate said bar to the initial position thereof permitted by the adjustment of the wheel 21 prior to its release of the rack-bar at the rearmost limit of movement of the latter is prevented by the frictional engagement of the teeth 21^a thereof with the teeth of said 45 rack-bar. But, when said rack-bar is released, the spring 28 exerts sufficient force to thrust said wheel into operative relation to said finger, the latter thereupon entering the channel 29 at the proper point provided for by adjustment of said gauge-bar 33.
- 50 The gradually increasing downward inclination of the finger 30 required as it traverses the channel 29 toward the inner end thereof is permitted by the pivotal connection of said finger with the arm 44, said connection allowing vertical swinging movement of said finger.
- 55 Located outside each side of the frame 11 125 is a frame comprising housings 45 in which are journaled shafts 46 and 47 located in the same horizontal plane. Carried by said shafts 46 and 47 are large gears or sprocket wheels 48 and 49, respectively, and these 130

gears are connected by one of the heavy sprocket chains 13 hereinbefore referred to. Mounted stationarily upon said chain is a clip-like support 50 by which is carried 5 a cleaving blade 12, said blade being directed transversely through said support and being longitudinally movable with respect to the latter. A spring 51 interposed between the outer face of said support 50 and a collar 52 formed upon said blade tends to normally hold said blade in a retracted position. An anti-friction roller 53 carried by the outer end of said blade is disposed for travel in an endless channel 54 10 provided therefor in the upwardly and inwardly inclined face 55^a of a block 55, hereinafter termed a cam-block, which surrounds an upright longitudinally extending supporting member or web 56. Said channel 54 constitutes a guideway in which the outer end of the blade travels as the latter is carried by the chain 13. Both the upper and lower portions or traverses of said channel extend horizontal throughout 25 a distance substantially corresponding to the length of the pack which is to be acted upon and said traverses are joined at each of the opposite ends by an arcuately curved and inclined portion 54^a. As the blade is carried through the foremost inclined portion 54^a, it is gradually thrust inward against the tension of its spring 51 until it occupies the advanced operative position shown in Fig. 1. When in the fully retracted position occupied when traversing the lower traverse of the guideway, the point of the blade is disposed outside the frame 11; but, as it is advanced toward its operative position, as aforesaid, it enters a 30 slot 57 provided therefor in the adjacent side of said frame and travels in said slot until its fully retracted position is again assumed at the rear end of the cam-block. Motion is communicated to the gear 49 for driving the blade-carrying chain 13 by means of intermeshing gears 58 and 90 carried respectively by shafts 59 and 47, the former being journaled in the lower rear end of the housings 45, and said shaft 59 40 is driven by a belt 60 connecting a thereby-carried belt wheel 61 to a similar wheel 62 carried by one of the rolls of the roll train hereinbefore referred to. A second belt wheel 63 carried by said shaft 59 is 45 connected by a drive belt 64 to a similar wheel 65 carried by a shaft 66 journaled in the lower front end of said housings 45; and a second belt wheel 67 carried by said shaft 66 is connected by a belt 68 to a belt 50 wheel 69 carried by an end of a shaft or spindle 70 which is mounted for rotary movement in the upper front ends of the adjacent side of the frame 11. Loosely mounted upon said spindle 70 inside the 55 sides of said frame 11 is a sleeve 78 hav- ing an arm 71 which depends vertically therefrom and which has upon its lower end a fixed rearwardly extending jaw 72 forming a part of a pair of tongs by which the front end of the pack is gripped during the preliminary downward bending of the corners of the pack, effected by means of the knockers 9. The cooperating member or jaw 73 of said tongs overhangs said jaw 72 and has its rear end connected by 60 an inclined pivoted link 74 to the lower end of the arm 71. A second link 75 is pivotally connected at its lower end to a side of the upper, or movable, jaw 73 at a point adjacent to the point of the latter, and is 65 thence upwardly and forwardly inclined and has its upper end pivoted upon a crank-pin 76 carried by a crank-arm 77 which is fixed on said spindle 70. Said spindle is driven at low speed and in such time with respect to the operation of the cleaving blades as to actuate the tongs to close upon or firmly grip and support the front end of the pack at the moment when the knockers act to 70 bend downward the corners of the lowermost sheet. As is apparent, the upper jaw of each pair of tongs is actuated by the crank-arm 77 to swing toward and away from the lower or fixed jaw during each 75 revolution of said arm. As each sheet is severed from the pack, it drops of its own weight to the bed, and, due to its flexibility, its front end slides from the underlying lower jaws of the tongs. 80

The knocker-heads 8 act upon the corners of the pack in a manner to effect a slight slipping movement of the sheets upon each other, as when the corners of the leaves of a book are abruptly flexed. 85

Each knocker 9 is very accurately spaced with respect to the adjacent end or corner of the pack when the latter occupies its forwardly drawn position, and the springs 80 employed possess such accurately adjusted tension or resistance that they yield for allowing the heads 8 to pass over the ends of all of the various sheets of the pack, except the lowermost sheet, with practically infinitesimal bending. Otherwise stated, the resistance offered by the springs is insufficient to hold the heads 8 of the knockers projected to the extent that the latter are maintained rigid enough to prevent any substantial bending of more than one sheet at a time, but they do offer such resistance to inward movement of said heads that the latter will effect an abrupt bending, or initial separation, of the unsupported corner of the lowermost sheet of the pack. 90

Each knocker 9 comprises a body portion fixed on the spindle 10. Pins 79 are directed through and are longitudinally movable with respect to said body, and mounted upon the opposite ends of said pins are the heads 8. Coil springs 80 interposed between said 95

heads and the adjacent ends of said body, render said heads readily yieldable so that the blows struck thereby are relatively light and effect permanent downward bending of 5 the corners of the lowermost sheet only of the pack, such lowermost sheet alone being unsupported from beneath.

Briefly stated, the operation of the machine is substantially as follows: As the final 10 sheet of a pack is dropped by the lifting magnets 7, the finger 30 rides from the channel 29 of the rotating wheel 21 to the central elevated surface of said wheel and thereby effects shifting movement of the latter on 15 its shaft 20 to a position overlying the rear end of the rack bar 22; then, as said wheel 21 is rotated, the teeth 21^a thereof engage the teeth of said rack bar and effect retracting movement of the latter to a point where- 20 in the magnets 7 overlie the front end of a sheet-metal pack which has previously been delivered to the platform 6 by the feed rolls. At this point in the operation, said magnets 7, which have temporarily been deenergized 25 are caused to be re-energized (by means not shown) and seize the front end of the pack. Immediately thereafter, the rack bar is released by the wheel 21, following which the then-compressed spring 86 re-expands thrust- 30 ing said rack bar forward to its initial position, drawing the pack forward therewith to a definite predetermined position. Upon the next rotation of the knockers, the heads 8 thereof act upon the end of the lowermost 35 sheet of the pack, as hereinbefore described, for bending the latter away from the next sheet thereover. The cleaving blades 12 then enter between the said lowermost sheet and the next sheet thereover and act to sever the 40 former from the pack in the manner hereinbefore indicated, said blades being carried rearward throughout the length of the pack. The bending of the edge of the lowermost 45 sheet by the knockers and the subsequent severing of said sheet is repeated in rapid succession until all sheets in the pack have been detached.

Following the release of the retracted rack bar by the wheel 21, the latter is shifted by 50 the spring 28 away from said rack bar and into a position wherein the finger 30 re-enters the channel 29 of the wheel at a point determined by the previous manual position- 55 ing of the bar 33 in accordance with the number of sheets in the just-advanced pack. Re-positioning of the locking pin 43 is not resorted to until a pack containing a different number of sheets is advanced to the sheet-separating position.

As hereinbefore explained, the blades 12 are retracted following each cleaving operation to permit of their return to pack-entering position.

The parts of the mechanism described are timed to operate so that each performs its

function in its proper sequence and in definite timed relation to the operations of the other cooperating parts. The gearing and driving connections herein shown are illustrative only and it will therefore be understood that the same may be appropriately modified, as desired.

What is claimed is—

1. A machine for opening sheet-metal packs, comprising feed rolls, means for advancing and supporting a pack following its passage through said rolls, cooperating blades, and mechanism for carrying said blades throughout a path in which they successively sever the lowermost sheet from the advanced pack.

2. A machine for opening sheet-metal packs, comprising feed rolls, means for advancing and supporting a pack following its passage through said rolls, cooperating blades, and mechanism for actuating travel of said blades throughout a path in which they successively sever the various sheets from the pack.

3. A machine for opening sheet metal packs, comprising means for supporting a pack horizontally, means for initially separating an end of the lowermost sheet from the pack, knife-blades arranged in opposing cooperative relation, and means for carrying said blades throughout a path in which they enter between said separated end and the pack and thence traverse the length of the pack for cleaving said lowermost sheet from the pack.

4. A machine for opening sheet metal packs, comprising means for supporting a pack horizontally, means for initially separating an end of the lowermost sheet from the pack knife-blades arranged in opposing cooperative relation, and means for carrying said blades throughout a path in which they enter between said separated end and the pack and thence traverse the length of the pack for cleaving said lowermost sheet from the pack, said separating means and said cleaving means being actuated successively until all sheets of the pack are separated.

5. A machine for opening sheet metal packs, comprising a pack carrying and supporting device, means for retracting said device to a position in supporting relation to a pack, means for advancing said device following its release by said retracting means, for advancing the pack, means for acting to successively produce initial separation of an end of the lowermost sheet of the advanced pack, knife blades arranged in opposing cooperative relation, and means for actuating said blades to enter between said separated ends and the overlying portions of the pack and thence to traverse the length of the pack for cleaving said sheets from the overlying portions of the pack.

6. A machine for opening sheet metal

packs, comprising a pack carrying and supporting device, means for retracting said device to a position in supporting relation to a pack, means for advancing said device following release by said retracting means, for advancing the pack, means acting to successively produce initial separation of an end of the lowermost sheet of the advanced pack, knife blades arranged in opposing cooperative relation, means for actuating said blades to enter successively between said separated ends and the over-lying portions

of the pack and thence to traverse the length of the pack for cleaving said sheets from the overlying portions of the pack and 15 means whereby said retracting means are maintained inoperative during the time that a pack is supported in advanced position and are then rendered operative following the sheet separating operation. 20

In testimony whereof, I affix my signature.

JAMES CARAFILIDIS.
